UNITED STATES PATENT OFFICE.

WILHELM BOEHM, OF BERLIN, GERMANY.

DEVICE FOR STERILIZING MEDICAL INSTRUMENTS.

1,129,271.

Specification of Letters Patent. Patented Feb. 23, 1915.

Application filed May 15, 1913. * Serial No. 767,812.

To all whom it may concern:

Be it known that I, WILHELM BOEHM, subject of the Emperor of Germany, residing at 106. Gitschnerstrasse, Berlin, Germany, 5 have invented certain new and useful Improvements in Devices for Sterilizing Medical Instruments, of which the following is a specification.

This invention relates to a device for 10 sterilizing medical instruments, such as canulas and the like.

Hitherto canulas, when made of precious metals have been freed from germs by being subjected to glowing heat for a short 15 time before being used. Canulas and the like made of non-precious metals have had to be exposed to boiling heat for a long time. By means of the present invention such medical instrument, canulas and the 20 like may be very quickly sterilized by being exposed for example to the direct action of a flame. For this purpose the instrument to be sterilized, such as a canula is placed in a receptacle, which is adapted thereto so 25 that practically no air can be contained in it. Such a receptacle is heated for a short time, and in a few seconds a rapid and reliable sterilization is effected, such as has not been possible in the same time hitherto. 30 The heating may for example be effected directly in a flame (gas flame or lucifer match flame, and in urgent cases in the ash of a lighted cigar) and for this purpose the receiver may be made of suitable 35 glass, porcelain, steel, etc. As the receptacle itself is electrically conductive, or is surrounded by an electric resistance conductor, the heating may also be effected by electricity. Hereby the well known and satis- 40 factory method of sterilization by the application of great heat, employed for instruments made of precious metals, can also be employed for sensitive instruments such as canulas, etc., made of non-precious metals. 45 These receptacles need not of course surround the whole instrument, but only those parts of the same which must be made actually sterile. In the case of canulas the receptacle is therefore in the form of a 50 sleeve one end of which is closed.

In the accompanying drawings, Figure 1 is a view of a device constructed in accordance with the invention, made of glass; Fig. 2 illustrates the manner of using the

device; Fig. 3 is a view similar to Fig. 1 55 showing the device as made of metal, and Fig. 4 illustrates a modification.

Referring to the drawings, A designates the improved sterilizing receptacle which, as above described, may be of glass, porcelain or any suitable material and which is closed at one end and of such diameter that it will fit closely about a canula or other small medical instrument C.

In the form of the invention shown in 65 Fig. 3, the receptacle A' is made of metal of such character that the interior thereof will be heated to the desired degree when a current of electricity is passed through the body, the latter being represented as 70 provided with suitable positive and negative terminals for connection with a source of electric energy.

Instead of making the entire receptacle 75 of metal, as shown in Fig. 3, an electric resistance conductor B may, as shown in Fig. 4, be wound thereon or embedded therein.

The manner of using and the advantages 80 of a device such as herein described will be readily understood from the foregoing description and the drawing. The sterilizing receptacle effectually prevents oxidation of the canula during the sterilizing operation so that the instrument may be used without danger of infection. It will be 85 seen that any desired number of such devices may be carried in a small space and whenever it is desired to sterilize a canula or other small instrument the device can be quickly applied and easily heated so that 90 the instrument will be thoroughly sterilized by dry heat.

Having thus described the invention what 95 is claimed and desired to be secured by Letters Patent is:

1. The herein described method of sterilizing by dry heat canulas or other small medical instruments, susceptible to oxidation, comprising fitting about the body to be sterilized a casing or receptacle of suitable material which will prevent oxidation of the instrument while being heated, and applying heat to the casing.

2. An appliance for use in sterilizing by dry heat canulas or other small medical 105 instruments susceptible to oxidation, comprising a tube-like receptacle or container closed at one end and adapted to fit closely

about the body to be treated to prevent oxidation of said body when it is subjected to heat.

3. An appliance for use in sterilizing by dry heat canulas or other small medical instruments, susceptible to oxidation, comprising a tube-like receptacle or container, including an electric resistance conductor, adapted to fit closely about the body to be treated, whereby the interior of the recep-

tacle may be quickly heated to sterilize the instrument therein and oxidation of the latter will be prevented.

In testimony whereof I have signed this specification in the presence of two subscribing witnesses.

WILHELM BOEHM.
